United States Patent Office

Des. 176,793
Patented Jan. 31, 1956

176,793

SHOE RACK OR SIMILAR ARTICLE

Ila Kinzie, Dallas, Tex.

Application July 8, 1954, Serial No. 31,333

Term of patent 3½ years

(Cl. D80—10)

Fig. 1

I claim:

The ornamental design for a shoe rack or similar article, substantially as shown.
